[57] CLAIM

The ornamental design for a wall mounted folding diaper changing support, as shown and described.

DESCRIPTION

FIG. 1 is a front elevational view of a wall mounted folding diaper changing support showing my new design;

FIG. 2 is a rear elevational view thereof;

FIG. 3 is a reduced top, front, and left side perspective view thereof, shown in an opened position;

FIG. 4 is a front elevational view thereof, shown in an opened position;

FIG. 5 is a top plan view thereof, shown in an opened position;

FIG. 6 is a top plan view thereof;

FIG. 7 is a bottom plan view thereof;

FIG. 8 is a left side elevational view thereof;

FIG. 9 is a right side elevational view thereof;

FIG. 10 is a top, front, and left side perspective view thereof;

FIG. 11 is a left side elevational view thereof, shown in an opened position, the right side being a mirror image of that shown; and,

FIG. 12 is a top, rear, and right side perspective view thereof.
